LOCK AND SWITCH MECHANISM FOR
ELEVATOR SHAFT DOORS

Julius A. Schweig, St. Louis, Mo.

Application May 5, 1934, Serial No. 724,121

13 Claims. (Cl. 187—54)

This invention relates to lock and switch mechanisms for the motor operated shaft doors of electric elevators. It has for its principal object to devise a cheap and efficient lock and switch mechanism that will prevent the opening of the shaft doors when the car is not at a landing and which will prevent the operation of the car until all of the doors in the shaft are closed and locked. Other objects are simplicity of construction, compactness of design, ease of assembly and installation and easy access to all parts of the lock and switch mechanism. The invention consists in the lock and switch mechanism and in the combinations and arrangements of parts hereinafter described and claimed.

In the accompanying drawings which form part of this specification and wherein like symbols refer to like parts wherever they occur,

Fig. 1 is an interior view of an elevator shaft provided at one of the doors therein with a door lock and switch device embodying my invention,

Fig. 2 is an enlarged front elevation of said device and the parts cooperating therewith,

Fig. 3 is a horizontal section on the line 3—3 in Fig. 2,

Fig. 4 is a diagrammatic view illustrating the drive for the door operating sheaves,

Fig. 5 is a vertical section on the line 5—5 in Fig. 2, showing the cam carried by the car for releasing the door lock,

Fig. 6 is a front elevational view of the door lock and switch device and the mounting parts therefor, the cover plate of the housing of the device being removed to disclose the various switches,

Fig. 7 is a fragmentary view of the lock bar,

Fig. 8 is a vertical section on the line 8—8 in Fig. 6,

Fig. 9 is a horizontal cross-section on the line 9—9 in Fig. 6,

Fig. 10 is a vertical section on the line 10—10 in Fig. 9,

Fig. 11 is a side elevation of a portion of a lock and switch device of modified form,

Fig. 12 is a front view of said device with the cover plate of its housing removed,

Fig. 13 is a vertical section on the line 13—13 in Fig. 11; and

Fig. 14 is a wiring diagram showing the location of the various switches in the different power and control circuits.

Referring to the accompanying drawings, my invention is shown in connection with an electric elevator comprising a shaft A having a door opening B at each floor which is closed by a

vertical sliding door comprising upper and lower counterbalanced door sections C and D, respectively. Each of said door sections is provided along each vertical edge with an angle bar side rail 1, having an outstanding flange slidably arranged between two of the flanges of two upright angle bar guides, 2, one of which is secured to the adjacent jamb member of the door opening B.

The upper sections are hung on cable chains 3 that pass over sheaves 4 and 4a located within the shaft A adjacent the upper corners of the door opening B. One end of each door supporting chain is suitably connected to the adjacent lower corner of the upper door section C, and the other end of said chain is connected to the upper end of an upright rod 5, whose lower end is secured to the outer end of an arm 6 that projects horizontally from the adjacent upper corner of the lower door section D. By this arrangement, one door section acts as a counterbalance for the other, and the two sections move simultaneously towards and away from each other to close and open the door. The elevator construction thus far described is well known and it is considered unnecessary to illustrate it in detail.

The door on each floor is opened and closed by means of a separate door operating mechanism driven by a reversible torque electric motor 7, which can be stalled under a full load for several minutes without injury. The electric motor is secured to a bracket 8 that is secured by bolts to the adjacent angle bar door guides 2. The armature shaft 9 of the motor is provided with a pinion 10 that drives a gear 11 rotatable with the door supporting sheave 4 which is fixed to a shaft 12 journaled in the bracket 8. This shaft has a small gear 13 fixed thereto that drives a gear 14 fixed to one end of a shaft 15, which is journaled in said bracket and has a sprocket wheel 16 fixed to the other end thereof which drives an endless sprocket chain 17 located in a recess 18 provided therefor in the interior surface of the front wall of the elevator shaft A just above the lintel 19 of the door opening B. Said sprocket chain extends longitudinally of said housing to the opposite side of said door opening where it passes around a sprocket wheel 20 fixed to a shaft 21, which is journaled in a bearing 22 provided therefor in the adjacent door guides 2 and has the door sheave 4a fixed thereto. As shown in the drawings, the bracket 8 is provided with a lubricant containing housing 8a within which are enclosed the gears 10, 11, 13 and 14.

55

The hereinbefore described door operating mechanism which forms the subject matter of my copending application Serial No. 705,501, operates as follows: When the motor 7 is started the drive 5 thereof is transmitted to the intermeshing gears 10 and 11 to the sheave 4, thence through the intermeshing gears 13 and 14 to the sprocket wheel 16 and thence through the sprocket chain 17 to the sprocket wheel 20, which rotates with the 10 sheave 4a in a direction opposite to the direction in which the sheave 4 is rotated. The drive is then transmitted from the oppositely rotating door sheaves 4 and 4a to the door chains 3 supported thereon, thereby causing the two door 15 sections C and D to slide in the door guides 2. The two door sections are slid apart when the motor is operated in one direction and are brought together when the motor is reversed.

According to the present invention, each door 20 is equipped with a combined lock and switch actuating mechanism mounted on a bracket E that is secured at its upper and lower ends by bolts 23b to the same angle bar door guides 2 that support the motor supporting bracket 8. The 25 bracket E is located opposite the door arm 6 of the lower door section D in closed position thereof and is provided with a box or housing 23 having a front opening closed by a removable cover plate 23a. An upright lock bar 24 is attached 30 at its lower end to said door arm by means of a screw 25; and a guide angle 26 is bolted to the adjacent door guide 2 to hold said lock bar in vertical position as it moves up and down with the lower door section D. Said lock bar is further 35 guided in a slot 27a provided therefor in a plate 27 that is bolted to the top of the box 23.

The lock bar 24 is provided with a vertically elongated slot 24a adapted, in the closed position of the lower door section D, to be engaged by a 40 lug 28a at the free upper end of an upstanding lock arm 28, whose lower end is fixed to a horizontal rock shaft 29 journaled in the side walls of the box 23 near the upper end thereof. The lock arm 28 is located outside of the box 23 and is yieldably held in locking position against a stop lug 30 by means of a coil spring 31 interposed between the back of said arm and a lug 32 on the adjacent side wall of said box. The slot engaging lug 28a of the lock arm 28 is provided with 45 a reduced outer end portion 28b adapted to enter the slot 24a in the lock bar 24 when the door is not entirely closed and the slot is not in a position to receive the entire lug.

Secured to the lock arm 28 by means of a bolt 50 33 is an arm 34 which extends into the shaft A 55 and has a roller 35 journaled therein at its outer end adapted to be engaged by a suitable retiring cam 36 mounted on the elevator car F and controlled in the usual manner from a push button 60 control panel H mounted in said car. The arm 34 may be rotated on the bolt 33 to adjust the roller 35 relative to the cam 36 and then locked in the desired position of adjustment by tightening said bolt. By this arrangement, when the car arrives at the floor landing, the cam 36 on the 65 car F will engage the roller 35 and thus actuate the lock arm 28 in a direction which will disengage the lug 28a from the slot 24a in the lock bar 24 and thus permit the door to be opened. When 70 the car is started, the cam 36 is retired in the usual manner (not shown), thereby permitting the spring 31 to move the lock arm 28 into engagement with the slot 24a in the lock bar 24 and thus prevent opening of the door.

75 Mounted for vertical sliding movement in a

slideway provided therefor in the rear wall of the switch box 23 below the lock mechanism is a slide bar 37, which is provided at its upper end with a hook 38 that is supported on a lug 39a on the lower arm of a bell crank lever 39. This bell 5 crank lever is located in the box 23 opposite the lock arm 28 and is pivoted for vertical swinging movement on a stud 40 that projects from one side wall of the box. The other or upstanding arm of the bell crank lever 39 is provided with a horizontal pin 41 that engages a longitudinal slot 42a in the outer end of a rock arm 42 which is fixed to the lock arm supporting rock shaft 29 for rotation therewith. By this arrangement, when the lock arm 28 is in locked position, the slide bar 10 15 supporting arm of the bell crank lever 39 is in its uppermost position and said slide bar 37 is raised in the box 23; and when said lock arm is in unlocked position, said arm of said bell crank lever 20 is in its lowermost position thereby permitting said slide bar to slide downwardly in said box. The slide bar supporting arm of the bell crank lever 39 is provided with a convexly curved outer end 39b adapted, in the disengaged or unlocked 25 position of the lock arm 28, to bear against an inclined shoulder 37a on the slide bar 37, thereby preventing upward movement of said slide bar when said lock arm is in unlocked position. The slot-and-pin connection 42a, 41 between the other arm of the bell crank lever 39 and the rock arm 30 42 forms a lost motion connection between said arms which permits further unlocking movement of the lock arm when the slide bar has reached the end of its downward sliding movement.

The slide bar 37 is adapted to operate a plurality of vertically spaced circuit opening and circuit closing switches I, J, K, L and M enclosed in the box 23. One element of each of these switches comprises a pair of stationary contact posts 43 and the other element comprises a contact plate 44 movable with the slide bar 37 into and out of engagement with said contact posts. The stationary contact posts of each switch are fixed to a fibre insulating block 45, the insulating block for the contact posts of the bottom switch M being secured to the bottom of the box 23, and the insulating block of the contact posts of each of the remaining switches being each fixed to the outstanding flange of a separate angle 46 fixed to said box. Each of these angles extends crosswise of the slide bar 37 with its ends secured to the rear wall of said box on opposite sides of said slide bar, thereby serving as a means for holding said slide bar in its slideway. The movable contact plate 44 of each switch is slidably mounted 55 on a pin 47 mounted on a fiber insulating block 48 fixed to the outstanding flange of an angle 49 whose other flange is fixed to the slide bar 37 for movement therewith. The contact plate 44 is held in the pin 47 by means of a cotter pin 50; 60 and a spring 51 is sleeved on said pin between said contact plate and the fiber supporting block 48 for the pin 47 and serves to yieldably hold said contact plate against said cotter pin. With this arrangement, when the door is locked, the slide 65 bar 37 is raised and the uppermost switch I is closed and the remaining switches are opened; and when the door is unlocked, said uppermost switch is open and the remaining switches are closed.

The above switches are incorporated in an electrical wiring system which may be divided into three circuits; namely, a power circuit for the door operator; a control circuit for the door operator; and an elevator control circuit.

70 Referring to the wiring diagram shown in Fig. 75

14, the power circuit and door control circuit are coupled to three main power lines, N , N' and N^2 , respectively, of a three phase alternating current circuit. Included in the power circuit is a magnetic switch O coupled to the three main power lines. A second magnetic switch P is also coupled to said power lines so as to reverse the current in two phases from that of switch O . The magnetic switch O is adapted to start the motor 7 to open 5 the door; and the switch P is adapted to start said motor to close the door. A wire 64 is connected to the middle terminal of the switch O and to one terminal of the motor 7 for each door in the shaft. Another wire 64a is connected to the middle terminal of the switch P and to the wire 64. Other wires 65 and 66 are, respectively, connected to the two remaining terminals of the magnetic switch O and to one of the stationary contact posts 43 of the switches J and K of the lock and switch device 10 of each door. Other wires 65a and 66a are respectively connected to the two remaining terminals of the magnetic switch P and to the wires 65 and 66. The other stationary contact posts of the switches J and K of each lock and switch device 15 are connected to the two remaining terminals of each motor 7 by wires 67 and 67a, respectively. This completes the power circuit for the door operators.

The control circuit for each door operator comprises a wire 68 connected to the power line N^2 and to one contact of a toggle stop switch Q located on the push button control panel H in the elevator car F . Another wire 70 is connected to the opposite contact terminal of the stop switch Q and to one contact of a closing push button switch R and to one contact of an opening push button switch S . Both the closing push button switch R and the opening push button switch S are located on the push button control panel H . The wire 70 is also connected to one contact of a door opening limit switch T mounted on the door guide 2 just below the box 23. Wire 70a is connected to the other contact of the limit switch T and to one contact of a similarly mounted door opening limit switch T' . Wire 70b is connected to the other contact of the limit switch T' and to one of a pair of auxiliary contacts O' on magnetic switch O . A wire 71 is connected to the remaining contact terminal of the opening push button switch S and to one end of the magnetic coil of switch O , and also to the remaining auxiliary contact O' of said switch. The opposite end of said magnetic coil is connected by a wire 78 to one of the stationary contact posts 43 of the switch L in each switch box 23. The other stationary contact post of the switch L is connected by a wire 79 to the power line N' . Another wire 80 is connected to the remaining contact of the closing button switch R and to one end of the magnetic coil of switch P ; and the other side of said magnetic coil is connected by a wire 78a to the wire 78.

A push button control panel U , preferably of the key operated type, is located on the hall side of each door and is provided with one push button switch V for opening the door and one push button switch W for closing the door. One of the contacts of switch V , and one of the contacts of switch W are connected by wire 70d to one of the contact posts 43 of the switch M . The other contact post of the switch M is connected by wire 70c to wire 70. The remaining contact of the push button switch V is connected by a wire 71a to a wire 71; and the remaining contact of the push button switch W is connected by a wire 72a

to wire 72. This completes the control circuit for the door operating mechanism.

The elevator control circuit includes the normally closed switch I at each floor. A wire 80 is connected to one contact post 43 of the switch I and at the other end to one phase of the elevator control circuit. A wire 81 is connected to the other contact post of the switch I of the lower switch box and to one contact post of the switch I of the upper switch box. The remaining contact post of the switch I of the upper box is connected by wire 82 to the other phase of the elevator control circuit so that when the car switch is operated and switches I are closed, a closed circuit is established to operate the elevator.

Referring to Figs. 6 and 14, when the door is closed and locked, the switch I is closed by the pressure of the spring 51 against the contact plate 44 and the circuits at switches J , K , L and M are open so that both power and control circuits for the door motors are open and the door cannot be operated. However, as the circuit for the elevator control is closed by the switch I , the car will move when the car switch is operated to close said circuit.

The cam 36 on the car F is retired by power as the car switch is moved to run the elevator. As shown in Fig. 5, this type of cam is extended by gravity (when the car is stopped at a floor landing) and engages the roller 35 of the lock and switch mechanisms, and thereby unlock the door, open the elevator control circuit at switch I and close the power and control circuits for the door at the switches J , K , L and M . The opening and closing of the switch I will prevent operation of the elevator car and will permit operation of the doors. It is noted that as the cam 36 engages the lever 28 to operate the lock controlled switches, the elevator control circuit is opened first and before the door operating circuits are closed.

When the elevator car F arrives opposite the door that is to be opened, the operator opens the car operating circuit switch and thus causes the cam 36 to engage the roller 35 of the combined lock and switch at that door, thereby causing the elevator control circuit to open and then close the power and control circuits for the door. The operator operates the door opening push button S on the control panel H momentarily. This causes the power to flow between the main power lines N' and N^2 through the wire 68 to the stop toggle switch Q , through the wire 70 to the door opening push button switch S , through the wire 71 to the coil of the magnetic switch O , through the wire 78 to the stationary contact post of switch L and through the wire 79 to the main power line N' . This energizes the coil on switch O , which closes the contacts thereof, and this establishes a circuit from the stop toggle switch Q through the wire 70 to the limit switch T , through the wire 70a to the limit switch T' , through the wire 70b to the auxiliary contacts O' , through the wire 71 to the coil of the magnetic switch O , through the wire 78 to the stationary contact post of the switch L , and through the wire 79 to the main power line N' .

This will maintain the magnetic coil on the switch O in the energized condition after the finger is removed from the door opening button S and thus allow the power to flow through the closed switches J and K to start the motor 7 to open the door.

The door then starts its opening movement under power, which movement continues until the door arm 6 strikes the actuating lever on the

limit switch T, which opens the circuit between wires 70 and 70a or 70a and 70b. This interrupts the power flow through the magnetic coil on switch O, thereby causing the contacts thereof to open and stop the power flow to the motor 7. The limit switch T is located a short distance from the sill of the door and the momentum of the door will bring it down to the sill.

To close the door, the operator presses the closing button switch R on the control panel H of the car F. It is noted in this connection that said closing push button switch is arranged so that it must be constantly depressed to operate the door in the closing direction. When the closing button R is depressed, power flows between the two main power lines N' and N², through the wires 68 to stop toggle switch Q through the wire 70 to the closing push button switch R, through the wire 72 to the magnetic coil on the switch P, and through the wires 78a and 78, the switch L, and the wire 79 to the main power line N'. This energizes the coil on the magnetic switch P, which closes the contacts thereof to start the motor 7 to close the door, the power continuing to flow to said motor after the door is closed and until the operator releases the push button switch R.

It is noted that the door can also be operated from the push button control panel U located on the roomside of the elevator shaft, and that the key push button switch V is connected by the wires 71a and 71 to the magnetic coil on switch O to open the door. The key push button switch W is connected by wires 72a and 72 to the magnetic switch P to close the door, and the opening and closing operating circuits through the push button panel U are inoperative except when the car is stopped at the floor landing to cause the switch M to close.

40 Elevators having cars equipped with stationary cams require a slightly modified form of door lock and switch device for preventing the opening of the switch I of said device and the stopping of the car whenever it passes the door. As shown in Figs. 11, 12 and 13, the modified form of door lock and switch device is provided with an actuating mechanism that is operated by the opening movement of the door. The vertically slideable contact bar 37 is provided with a vertical slot 37b adapted to slidably receive a supporting member 52 that carries the movable elevator contact plate 44 of the upper switch I. The upper end of member 52 is provided with a plate 52a that projects beyond one side of the slide bar 37 where it is provided with a depending guide pin 52b on which is sleeved a coil spring 53. The upper end of this spring bears against the underside of the top plate 52a of the member 52; and the lower end of said spring rests on a seat 23c provided therefor in the box 23. By this arrangement, the force of the spring 53 tends to move the slide member 52 upwardly and force the contact plate 44 carried thereby against the contact posts 43 of the switch I and thus close the circuit controlled thereby. A bell crank 54 is journaled on a horizontal stud 55 fastened in the box 23, with one arm 54a in position to press downwardly against the top plate 52a of the slideable member 52 and with the other arm 54b in position to be actuated by an arm 56 pivoted on the rock shaft 29 that carries the cam actuated lock arm 28.

With this arrangement, downward movement of the lower door section D, arm 6 and lock bar 24 will cause the lower end of the lock bar 24

to swing the arm 56 inwardly to actuate the bell crank lever 54 and the sliding member 52 and thereby force said member downwardly against the tension of the spring 53 and open the switch I in the elevator control circuit. During the opening movement of the door, the inside face of the lock bar 24 will bear against the arm 56 the full distance of the door travel so that the circuit at switch I cannot be closed until the door is again completely closed.

Obviously the above described door operating mechanism admits of considerable variation without departing from the spirit of the invention. For instance, additional sets of contact, either normally closed or normally opened, can be attached in the switch mechanism as may be required for an automatic control system and when direct current power is used. Furthermore, numerous other changes may be made in the construction and location of the switch mechanism, door operating mechanism and motor control circuit illustrated, without departing from the invention.

What I claim is:

1. In an electric elevator, a shaft, a car working therein, doors for closing the door openings in said shaft, electric motors for opening and closing the respective doors, electric power and control circuits for said motors, a circuit for controlling the operation of said car, a lock for each door, a switch in said last mentioned circuit and associated with each door lock, and switches in said power and control circuits and also associated with said lock, said first mentioned switch being closed when said door lock moves to locking position and opened in the unlocked position of said lock, and said second mentioned switches being opened in the locked position of said lock and closed in the unlocked position thereof.

2. In an electric elevator, a shaft, a car working therein, doors for closing the door openings in said shaft, electric motors for opening and closing the respective doors, electric power and control circuits for said motors, a circuit for controlling the operation of said car, a lock for each door, a switch in said last mentioned circuit and associated with each door lock, and switches in said power and control circuits and associated with said lock and opened in such position thereof, said first mentioned switch being opened and said second mentioned switches being closed by the movement of said door lock to unlocked position.

3. In an electric elevator, a shaft, a car working therein, doors for closing the door openings in said shaft, electric motors for opening and closing the respective doors, electric power and control circuits for said motors, a circuit for controlling the operation of the car, a lock for each door, a switch operated by each door lock for closing the car control circuit in the locking position only of said door lock, switches in said power and control circuits and adapted to be opened in such position of said lock, limit switches in the motor control circuit operable and by the respective doors at the end of their opening movement to open said circuit, switches mounted respectively on the car and on the roomside of the elevator shaft for closing the motor control circuit to open and close the respective doors, and a switch on said car and located in the control circuit for said motors for controlling the operation of said doors.

4. In an electric elevator, a shaft, a car working therein, doors for closing the door openings

- in said shaft, electric motors for opening and closing the respective doors, electric power and control circuits for said motors, a circuit for controlling the operation of the car, a lock for each door, a switch associated with each lock for interlocking the car control circuit with the power and control circuits for said motors in the locking position of said lock, and switches in said power and control circuits and associated with 5 said lock for opening said circuits in said position of said lock, said first mentioned switch being opened and said second mentioned switches being closed by the movement of said lock to unlocking position.
- 15 5. In an electric elevator, a shaft, a car working therein, a vertically slidable door in said shaft, an upright lock bar movable with said door, and a locking device for said door, said device comprising a bracket secured to said shaft, a 10 lock arm pivoted on said bracket for vertical swinging movement into and out of locking engagement with said lock bar, a spring for swinging said lock arm to locking position, a cam on said car for disengaging said lock arm from said 15 lock bar, an electric switch comprising a contact element fixed to said bracket and a normally closed spring-pressed movable contact element, and a lever mounted on said bracket and directly operable by said lock bar in the open position 20 of said door to disengage said movable contact element from said fixed contact element.
- 25 6. In an electric elevator, a shaft, a car working therein, doors for closing the door openings in said shaft, electric motors for operating the 25 respective doors, a combined lock and switch device for each door, said device comprising a housing secured to the elevator shaft, a lock arm pivoted in said housing and adapted to be automatically swung into locking engagement with said door in the closed position thereof, an arm adjustably secured to said lock arm, a cam on 30 said car adapted to actuate said arm to release said lock arm from said door, and a plurality of switches mounted in said housing, some of said 35 switches controlling the operation of the door operating motors, each of said switches comprising fixed and movable elements, the movable elements of said switches being operatively connected with said lock arm so as to be actuated 40 thereby.
- 45 7. In an electric elevator, a shaft, a car working therein, doors for closing the door openings in said shaft, electric motors for operating the 45 respective doors, a combined lock and switch device for each door, said device comprising a housing secured to the elevator shaft, a lock arm pivoted in said housing and adapted to be automatically 50 swung into locking engagement with said door in the closed position thereof, a cam on said car adapted to release said lock arm, a bar slidably mounted in said housing and operatively connected with said arm to be slid thereby in one direction during the movement of said arm to locking 55 position and in the opposite direction during the movement of said arm to unlocking position, and a plurality of switches enclosed in said housing, each of said switches comprising an element fixed to said housing and an element movable with said 60 slide bar into and out of engagement with said 65 fixed element.
- 70 8. In an electric elevator, a shaft, a car working therein, doors for closing the door openings in said shaft, a locking device for each door, said device comprising a housing secured to said shaft, a lock arm pivoted in said housing and adapted 75 to be automatically swung into locking engagement with said door in the closed position thereof, a cam on said car adapted to release said lock arm, a plurality of switches located in said housing comprising fixed and movable contact elements, a bar slidably mounted in said housing and having the movable contact elements fixed thereto, a bell crank lever pivoted in said housing with one arm operatively engaging said bar to actuate the same, an arm mounted in said housing for movement with said lock arm, and a slot-and-pin connection between said last mentioned arm and the other arm of said bell crank lever.
9. In an electric elevator, a shaft, a car working therein, doors for closing the door openings in 15 said shaft, electric motors for operating the respective doors, electric power and control circuits for said motors, an electric control circuit for said car, a combined lock and switch device for each door, said device comprising a housing secured 20 to the elevator shaft, a lock arm pivoted in said housing and adapted to be automatically swung into locking engagement with said door in the closed position thereof, a cam on said car adapted to release said lock arm, a bar slidably mounted 25 in said housing and having a bell crank lever pivoted in said housing with one arm operatively engaging said bar to actuate the same, an arm mounted in said housing for movement with said lock arm, a slot-and-pin connection between said 30 last mentioned arm and the other arm of said bell crank lever, a plurality of switches enclosed in said housing and located in the power and control circuits for the door operating motors, and a switch enclosed in said housing for connecting the motor power and control circuits with the car control circuits, each of said switches 35 comprising a contact element fixed to said housing and an element movable with said slide bar.
10. In an elevator, a shaft, a car working therein, sliding doors for closing the door operating openings in said shaft, a locking device for each door, said device comprising a housing fixed to said shaft, a lock arm pivoted on said housing, a spring for yieldably holding said lock arm in locking position, a cam on said car for moving said lock arm to unlocking position, said housing having a stop thereon for limiting the movement of said lock arm to locking position, and a lock bar movable with said door and adapted to hold 40 said lock arm in unlocked position in the open position of said door, said lock bar having a slot 45 therein adapted to be engaged by said lock arm in the closed position of said door.
11. In an elevator, a shaft, a car working therein, sliding doors for closing the door operating openings in said shaft, a locking device for each door, said device comprising a housing fixed to said shaft, a lock arm pivoted on said housing, a spring for yieldably holding said lock arm in locking 50 position, a cam on said car for moving said lock arm to unlocking position, said housing having a stop thereon for limiting the movement of said lock arm to locking position, a lock bar movable with said door and having a slot therein 55 adapted to be engaged by said lock arm in the closed position of said door, a guide on said housing for said lock bar, and a guide on said shaft for said lock bar, the slot sliding engaging portion of said lock arm terminating at its end in 60 a portion of reduced width.
12. In an electric elevator, a shaft, a car working therein, an electric circuit for controlling the operation of said car, doors for closing the door openings in said shaft, electric motors for oper- 75

ating the respective doors, electric power and control circuits for said motors, and a combined lock and switch device for each door, said device comprising a housing secured to said shaft, a lock arm pivoted on said housing and adapted to automatically swing into locking engagement with said door in the closed position thereof, a cam on said car for unlocking said lock arm, a bell crank lever pivoted in said housing, an arm mounted in said housing for movement with said lock arm and having a slot-and-pin connection with one arm of said bell crank lever, a bar slidably mounted in said housing and operatively connected to the other arm of said bell crank lever to be actuated thereby, and a plurality of electric switches enclosed in said housing, each of said switches comprising a contact element movable with said bar and a contact element fixed to said housing, one of said switches being adapted to 10 interlock the car control circuit with the power and control circuits for said motors in the locking position of said lock arm, and the remaining switches being located in said motor power and control circuits and adapted to be opened in the locked position of said lock arm and closed in the unlocked position thereof.

13. In an electric elevator, a shaft, a car working therein, an electric circuit for controlling the operation of said car, doors for closing the door openings in said shaft, electric motors for operating the respective doors, electric power and

control circuits for said motors, and a combined lock and switch device for each door, said device comprising a housing secured to said shaft, a lock arm pivoted on said housing and adapted to automatically swing into locking engagement with said door in the closed position thereof, a cam on said car for unlocking said lock arm, a bell crank lever pivoted in said housing, an arm mounted in said housing for movement with said lock arm and having a slot-and-pin connection with one arm of said bell crank lever, a bar slidably mounted in said housing and operatively connected to the other arm of said bell crank lever to be actuated thereby, a plurality of electric switches enclosed in said housing for making and braking the power and control circuits for said motors, each of said switches comprises a contact member fixed to said housing and a contact member movable with said bar into and out of engagement with the fixed contact in the locking and unlocking positions, respectively, of said lock arm, an independent switch enclosed in said housing for interlocking the car control circuit with the power and control circuits for said motors in the closed position of said door, said interlocking switch including a normally closed movable contact member, and means on said door cooperating with said last mentioned contact member for holding it open when the door is open.
